L. C. SMITH.
HEATING APPARATUS.
APPLICATION FILED DEC. 26, 1917.

1,303,977.

Patented May 20, 1919.

UNITED STATES PATENT OFFICE.

LEONARD C. SMITH, OF NEW YORK, N. Y.

HEATING APPARATUS.

1,303,977.

Specification of Letters Patent. Patented May 20, 1919.

Application filed December 26, 1917. Serial No. 208,834.

To all whom it may concern:

Be it known that I, LEONARD C. SMITH, a citizen of the United States, and a resident of the borough of Manhattan, in the city of New York, county and State of New York, have invented certain new and useful Improvements in Heating Apparatus, of which the following is a specification.

The invention relates to heating apparatus and particularly to a device or attachment which is applied to or used in conjunction with a radiator. The device or attachment is particularly useful when applied to a radiator that is part of a heating system, such as a steam or hot water radiator employed, for example, in dwelling houses, office buildings and apartments.

As illustrating a specific embodiment of the invention reference is made to the accompanying drawing forming a part of this specification and in which drawing,

Figure 1 is a side view of a radiator with the device or attachment applied thereto.

Fig. 2 is an end view of a radiator showing the device or attachment in position relative to the radiator.

Fig. 3 is a plan view showing a form of heating coil that constitutes a part of the device or attachment.

Fig. 4 is a vertical view substantially hollow in cross-section showing some of the fittings and piping employed in the device or attachment.

The radiator is designated by 1. It is ordinarily supplied with the heating medium, as for example steam, through valve controlled supply piping 2. This piping includes the ordinary radiator valve or hand stop valve 3. As is well known, when said valve controlled supply piping 2 is closed no heating medium is being supplied to the radiator.

The radiator is shown as having associated therewith an attachment A which may be considered as connected to the lower far end of the radiator since it is connected to the lower part of the radiator and to the end which is farthest from the place where the heating medium is usually supplied. In many radiators, at this place there is provided a screw-plug which seals said lower far end of the radiator.

According to the present invention, in place of the plug usually employed there is inserted at the lower far end of the radiator

a special screw-plug or fitting 4. If by chance the radiator is not provided with a threaded opening at this place then the device or attachment may be applied as by boring a hole in the radiator, threading and then inserting the shaped screw-plug 4 in an obvious manner; or, if the radiator is a double pipe system it may be connected in the piping between a radiator valve and the radiator. This special screw-plug or fitting 60 4 has a longitudinally extending upper conduit or passageway 5 and a lower conduit or passageway 6 which may be referred to as the inlet and outlet passageways respectively. The special screw-plug 4 is hollow 65 and the inner or radiator end thereof is threaded on the exterior where it enters the threaded opening in the radiator. The plug is threaded as at 7 and receives therein a bent pipe or inwardly and upwardly extending 70 tube 8, the function of which tube is to direct incoming hot water or steam into the upper portion of the base of the radiator whereby a proper circulation will be set up in the radiator when the device or attachment is employed, as will hereinafter appear. The special screw-plug 4 is also threaded, as at 9, and receives therein the horizontally extending connecting tube 10. This tube 10 is connected to the T or fitting 75 11 into which T there is screwed a valve controlled cup-member 12 that serves as a means for permitting the insertion of the circulating water, when desired. The lower part of the special screw-plug 4 is threaded, as at 13, 80 90 and receives the upper end of a vertically extending or depending pipe 14. The lower end of said pipe 14 is connected to an elbow 15 at one end of a heating coil 16 and leads from the lower hollow interior portion of 95 the plug or special fitting to the heating coil. The other end of said heating coil has an elbow 17 connected to the T 11 by the substantially vertically extending or upstanding piping which includes the members 18, 19 100 20 and which leads from the heating coil to the upper passageway in the special fitting. The heating coil 16 is preferably heated by means of a gas burner B which is supplied with gas, as through piping 21, 105 controlled by hand valve 22. If desired other means could be employed for heating the coil as, for example, electrical means. A hood C may be placed over the burner and heating coil 16 from which hood products of 110

combustion can be conducted from the room, if desired, through an opening or passageway 23.

It is well known that when radiators are closed, for example steam radiators where there is only a single piping both for feeding steam to the radiator and for conducting steam therefrom, more or less water of condensation will collect in the lower portion of the radiator. If the radiator valve or hand stop valve 3 is closed, it may be that in many instances enough water of condensation will collect in the bottom of the radiator to provide the required circulating water when the device or attachment is in use, in which case further water will not be added prior to employing the device or attachment in performing its desired function. Whether or not there is sufficient water within the radiator is readily determined, as by opening the hand valve 24, and if there is not the desired amount of water then it can be supplied through the cup-shaped member 12 the valve 24 of which is now open. When the desired amount of water is in the radiator the valve 24 is closed—if not already closed—the stop valve 3 still remains closed, and the device or attachment is ready to be operated. This is accomplished by opening the valve 22 of the gas supply and lighting the burner B.

As the water in the coil heats it is caused to circulate in the direction indicated by the arrows, that is the hot water passes from the coil 16 through elbow 17, members 18, 19, 20, 35 T or fitting 11, tube 10, upper inlet passage-way 5 and directing tube 8 through the radiator. The cooler water flows from the radiator through the lower outlet passageway 6, pipe 14 and elbow 15 into the heating coil 40 where it is heated and again caused to be circulated.

The device or attachment is applicable to a radiator which is connected in what is ordinarily known as the double piping system and it is also applicable to a radiator where the heat for the radiator is to be supplied solely by the employment of the device or attachment.

The device or attachment is particularly applicable to a radiator located in a room where the ordinary supply of heat thereto is interrupted or cut off, as for example by the early banking of a furnace, or due to the usual supply being temporarily out of commission. The device is applicable not only to a radiator used in a steam heating system but also to a radiator employed as a part of a water heating system.

It will also be noted that the device or attachment is constructed so that the heating

coil, which may be broadly considered as a water chamber member, the gas burner and the hood covering said coil and burner are all located between the floor supporting the radiator and the base or bottom portion of the radiator. This provides a neat, compact construction which affords to the device or attachment such an arrangement of parts that it is readily applicable to radiators already installed. The heating portion of the heating coil is located at one end of the special fitting or plug and is also at a lower elevation than the fitting or plug, as is manifest from an inspection of Fig. 1.

The radiator may have any suitable air or vent valve as V, and if desired this valve V can be embodied in the form of a safety valve construction to permit of the escape of excess pressure, when desired.

The improvements herein set forth are not limited to the precise construction and arrangement shown and described for they may be embodied in various forms and modifications without departing from the spirit and scope of the invention.

What I claim is:

An attachment to be applied to the far end of a radiator for supplying auxiliary heat to said radiator, comprising a plug adapted to be screwed into the aforesaid end of the radiator, said plug having a horizontally disposed conduit therein communicating with the interior of the radiator, a pipe threaded into the underside of the said plug and in constant communication with the said conduit, a horizontally disposed heating coil extending beneath the radiator and having one end connected to said pipe, a hood inclosing said heating coil, an upwardly extending pipe screwed into the plug above the horizontally disposed conduit in said plug, the other end of said pipe passing to the interior of the radiator, a horizontally disposed pipe threaded into the plug at the side opposite the said upwardly extending pipe, the two pipes being in alinement and communicating with each other through a conduit in the plug above the first named conduit, connecting means extending between the last named horizontal pipe and the heating coil, and a valve controlled conduit communicating with both the heating coil and the radiator.

This specification signed and witnessed this 22nd day of December, A. D. 1917.

LEONARD C. SMITH.
